BUTTON-SEWING MACHINE.

1,149,474.

Specification of Letters Patent. Patented Aug. 10, 1915.

Application filed November 14, 1912. Serial No. 731,241.

To all whom it may concern:

Be it known that we, JOHN J. SULLIVAN and ALBERT F. FIFIELD, citizens of the United States, residing, respectively, at 5 Ipswich, in the county of Essex and State of Massachusetts, and Bridgeport, in the county of Fairfield and State of Connecticut, have invented certain new and useful Improvements in Button-Sewing Machines, 10 of which the following is a specification, reference being had therein to the accompanying drawings.

This invention relates to an improvement in button-fastening machines, and more particularly of that class comprising stitch-forming mechanism, a presser-foot having a button-guideway adapted for directing a button into fastening position, a chute in register with said guideway, and a button-carrier or propeller adapted to convey the buttons successively from the mouth of the chute through the guideway of the presser-foot into fastening position.

The invention has for some of its objects 25 to insure the location of the button within fastening position in the presser-foot before the descent of the latter to clamp the work for the fastening operation; to facilitate the movement of the button from the chute into 30 fastening position; to provide simple means for yieldingly gripping the buttons in their travel from the supply to the holding member; to provide means which are positively acting in conveying the button from the 35 chute and yieldingly acting in positioning the same for the fastening operation; and to insure a certainty of delivery of the buttons from the supply-hopper to the chute.

In its preferred form the machine is constructed with an endwise reciprocating bar disposed slightly above and parallel with the work-support and provided with button-engaging means adapted to receive a button at the lower end of the chute and 45 move the same through the guideway of the presser-foot into the range of action of the button-fastening means, such bar being supported by swinging arms mounted upon parallel fulcra beneath the same and connected with a vibratory controlling lever of the stop-motion device for effecting the starting and stopping of the stitch-forming or other fastening means. The button-carrier and presser-foot lifting devices are so

constructed and independently connected 55 with the stop-motion that in the manual operation of the latter to start the machine, the button is first advanced into position, the presser-foot then lowered and the fastening mechanism thereafter set in motion, 60 thereby obviating the forcible resistance to the advance of the button heretofore imposed by the premature lowering of the presser-foot upon the work and the thrusting of the button forward into contact with 65 the work under the action of the presser-foot. The button propelling bar is preferably provided with a rigid button-propelling jaw and a laterally movable button-clamping jaw which latter is mounted upon 70 a rock-lever fulcrumed upon said bar and normally pressed by means of a spring into button-engaging position. The swinging supporting arm nearest the button-carrier so constituted is provided with a cam-member 75 which engages said rock-lever, when the carrier is retracted to receive a button from the mouth of the chute, so as to shift the clamping jaw temporarily out of operative position to which it is permitted to return 80 in the advance of the carrier to fastening position. The rock-lever member of the carrier is provided with a button-detaining spring-finger extending in advance of its 85 clamping jaw and adapted to detain the foremost button of the chute in the retracted position of the carrier until the advance of the latter to fastening position, during which the lower button is securely gripped and the one above it caused to rest upon 90 the top of the advancing carrier where it remains until the retraction of the carrier 95 after a button-fastening operation. The hopper for supplying the buttons to the chute may be provided with an agitator mounted upon a shaft to which is imparted step-by-step rotary movements by means of ratchet-and-pawl mechanism, the agitator-shaft having frictionally mounted thereon a spring-retracted arm confined to a range 100 of vibratory movement less than the angular movement which would be normally imparted thereto under the action of the ratchet-and-pawl mechanism. By this means, for each step of advance movement 105 of the agitator it performs a backward movement of less extent, thereby producing a more effective agitation of the buttons

than when receiving operative movements invariably in the same direction.

In the accompanying drawings, Figure 1 is a rear side elevation of a button sewing machine embodying the present improvements. Fig. 2 is a plan of the lower portion of the same with the standard in transverse section. Fig. 3 is an enlarged front end view of the work-supporting arm and the adjacent portions of the button-handling devices. Fig. 4 is an elevation, looking toward the front of the machine, of the lower portion of the button-chute, the button-carrier and the cam-member for controlling the button-clamping jaw. Fig. 5 is a perspective view of the same parts with one member of the button-chute partially removed. Fig. 6 is a perspective view of a portion of the stop-motion device, and Fig. 7 a perspective view of the controlling cam and an element of the stop-motion engaged thereby. Fig. 8 is a perspective view of the presser-foot taken from the lower side. Fig. 9 is an elevation of the actuating mechanism of the button-agitator, and Fig. 10 a bottom plan of a portion of such mechanism. Fig. 11 is a perspective view of the agitator shaft carrying the bushing with the ratchet-wheel mounted thereon.

As represented in the drawings, the present improvement is applied to a Singer button sewing machine of which the frame is constructed with the usual hollow standard 1 with the laterally extending tubular work-supporting arm 2 and the overhanging bracket-arm 3 in the head 4 of which is fulcrumed the swinging needle-bar frame 5 having journaled therein the usual reciprocating needle-bar 6 carrying the needle 7 which coöperates with the shuttle 8 journaled in the race 9 of the work-supporting arm 2 in the production of the fastening stitches. Journaled also in the bracket-arm head 4 is the presser-bar 10 normally pressed downwardly by means of the spring 11 surrounding the same and having secured to its reduced lower end by means of the fastening screw 12 the channeled shank 13 of the presser-foot 14. The presser-foot has the usual needle-aperture 15 rearward of which it is cut away to form the flat vertical button-head seat or guideway 16 intersected by the inclined and upwardly flaring slot 17 affording a button-shank guideway beneath which are the lips 18 depending slightly below the lower fabric-engaging faces 19 separated by the elongated needle-aperture.

Mounted upon the top of the bracket-arm is the base 20 of the button-hopper embraced by the cylindrical casing 21 having the usual discharge aperture at one side leading into the upper end of the button-chute comprising the inclined bar 22 with central longitudinal button-shank guiding slot 23 and overlying bar 24 affording be-

tween them a button-head guideway whose mouth at the lower end is in register with the guideway of the presser-foot when elevated. The lower extremity of the bar 22 extends close to the adjacent edge of the 70 presser-foot, so that the button-shank slot 23 is in substantial alinement with the slot 17 of the presser-foot, but the lower end of the bar 24 is cut away above the slot 17 substantially parallel with the operative work-supporting face 25 of the throat-plate 26 sustained by the work-supporting arm 2.

Sustained slightly above the work-supporting arm 2 and beneath the arm 3 is the endwise reciprocating bar 27 having secured upon its forward end the apertured boss 28 of a block 29 formed at its forward extremity with the button-engaging shoulder or jaw 30 and upon its upper side with the button-supporting rib 31 having a downwardly inclined forward portion and adapted to traverse a path, in the movement of the carrier, beneath the mouth and at an inclination with the chute and the lower extremity of the member 24 thereof, so as to 90 sustain the lowermost button within the chute when the carrier is in advance or button-attaching position, as represented in Fig. 5. The block 29 sustains the vertical fulcrum-pin 32 upon which is mounted for 95 lateral movement the rock-lever 33 having a forwardly extending arm 34 formed with a transversely offset lateral button-engaging face or jaw 35 and with a rearwardly extending arm 36 normally pressed outwardly 100 by means of the spring 37 interposed between the same and the end of a socket in the block 29. The arm 34 has secured to its outer face by means of the screw 38 the wire spring 39 whose free end portion 40 extends 105 transversely through the slot 41 in the member 35 and affords a yielding button-detaining finger normally disposed in register with the mouth of the chute when the carrier is in retracted position. The forward portion of the bar 27 adjacent the boss 28 is embraced by and clamped by means of the screw 42 within the split socket 43 forming the head of the transverse fulcrum-pin 44 which is journaled within and sustained by 110 the transverse boss 45 of an upwardly extending swinging arm 46 having at its opposite end the boss 47 which is fixed upon the rearward end of the transverse pivotal pin 48 journaled in the lower portion of the 115 work-supporting arm 2 in which it is held in position by means of the screw 49 and washer 50. The fulcrum-pin 44 is maintained in position within the boss 45 by means of the screw 51 and washer 52. The 120 boss 45 has an extension 45' upon which is adjustably secured by means of the clamp-screw 53 the split hub 54 of the cam-arm or member 55 whose front face affords a forwardly and downwardly inclined cam sur- 130

face 56 for operative engagement with the similarly inclined adjacent face of the rock-lever arm 36. The forward portion of the bar 27 sustaining the carrier is thus supported by the swinging arm 46 which, in the retracted position of the carrier is substantially vertical, but swings forwardly in the advance of the carrier and downwardly around the pin 48 as a fulcrum, as represented in dotted lines in Fig. 1, so as to cause the carrier to follow substantially the inclination of the button-shank slot 17 of the presser-foot to facilitate the advance movement of the button into fastening position. As the cam-member 55 is rigidly connected with the arm 46, it is caused to move downwardly about the pivotal pin 44 in the advance of the carrier, as represented in Fig. 5, for disengagement from the adjacent 20 face of the rock-lever arm 36, thereby permitting the clamping jaw 35 to grip the button engaged by the rigid jaw 30 for securely holding it for the fastening operation.

The bar 27 passes through a clearance 25 aperture 57 of the standard 1 having in its inner wall the annular seat 58 to receive the knurled thrust-collar 59 adjustably mounted upon the threaded rearward end 27' of the bar and secured in position thereon by 30 means of the set-screw 60. Secured upon the rearward end of the bar 27 by means of the set-screw 61 is the apertured socket of a block 62 pivotally connected by means of the screw-pin 63 with the upper end of the 35 swinging upper arm 64 of a rock-lever fulcrumed by means of the stud 65 upon a lug 66 extending from one side of the standard, said rock-lever having a depending arm 67 carrying the screw-pin 68.

40 Pivots connected with the rock-lever arm 67 by means of the screw-pin 68 is the forward section 69 of a two-part connecting rod whose rearward extremity is slidingly fitted within a socket 70' of the rearward 45 section 70 formed at its opposite extremity with the boss 71. The component sections of this rod are drawn together by means of a spring 72 having one end connected with a pin 73 depending from the boss 71 and the 50 other end connected with a pin 74 depending from a forward extension 69' of the section 69, the two sections being normally maintained in fixed relation by engagement of the forward extremity of the section 70 with 55 the adjacent end of the thrust-collar 75 applied to a threaded portion of the section 69 and secured in the desired position of adjustment thereon by means of the set-screw 76. The collar 75 is shown formed with an 60 annular groove to afford an abrupt shoulder 75' adapted for engagement with the hooked extremity 77 of the forward arm 78 of a rocking latch-lever mounted upon the fulcrum screw-stud 79 and between the spaced 65 ears 80 extending upwardly from the rod

section 70, such rock-lever having a rearwardly extending arm 81 adapted for engagement with the stationary conical-pointed tripping stud 82 having its threaded shank 83 tapped into the standard 1 and 70 maintained in the desired position of adjustment by means of the jam-nut 84. The latch-lever is normally maintained in operative relation with the collar 75 by means of the spring 85 connecting the forward arm 75 78 of the same with the rod section 70.

The boss 71 of the sectional connecting rod is pivotally attached by means of the screw-bolt 86 with the lower end of a depending arm 87 attached by screws 88 to 80 one edge of the vibratory stop-lever 89 which is fulcrumed by means of center-screws 90 between the ears 91 of a bracket 92 sustained by the standard 1, and has journaled therein the plunger-rod 93 whose 85 upper extremity is adapted to engage the operative side face and periphery of the stopping cam 94 fixed upon the main-shaft 95 of the sewing machine and provided with the peripheral notch 96 therein in arresting 90 the operation of the stitch-forming mechanism. The plunger-rod is normally pressed upwardly into operative position toward the main-shaft 95 by means of a surrounding spring 97 interposed between the upper end 95 of the bushing 98 in the lower member of the stop-lever 89 and the thrust-collar 99 adjustably secured upon the plunger-rod by means of the set-screw 100. The plunger-rod is thrown laterally into operative relation 100 with the cam 94 by means of the spring 101 interposed between the upper part of the stop-lever 89 and the standard 1, and is adapted to be disengaged therefrom, by means of the treadle-rod 102 connected with 105 the lateral arm 103 of the stop-lever 89.

The arm 103 carries upon one side the roller-stud 104 which is embraced by the forked extremity 105 of the lateral arm 106 of a bellcrank-lever fulcrumed upon the set-screw 107 sustained by the standard 1 and having an upwardly extending arm 108 carrying the roller-stud 109 normally resting upon the rearwardly extending flange 110 of the controlling cam-cylinder 111 loosely 115 journaled upon the main-shaft 95 and deriving step-by-step operative movements from well known actuating mechanism such as that disclosed, for instance, in the United States patent to P. Diehl and M. Hemleb, No. 568,338, of September 29, 1896. The arm 103 is drawn downward to shift the stop-lever 89 from full line position to the dotted line position (Fig. 1) when the notch 110' of the cam element 110 is in register 120 with the roller-stud 109, and is held down until the outer edge of the cam comes into operative relation with the stud 109, when the release of the arm 103 permits the stud 109 to roll in contact with the cam 110 under 125 130

the action of the spring 101 until the notch 110' again comes into register with it, whereupon the release of the bellcrank-lever 106 108 permits the stop-lever to regain operative position in which the plunger-rod 93 acts in conjunction with the stopping cam 94 in arresting the action of the machine, the usual driving belt having been previously moved from the grooved fast pulley 112 to the adjacent loose pulley 113. In the manual shifting of the stop-lever 89 to start the machine, the sectional connecting rod 69 70 is retracted and the rock-lever arm 64 consequently moved forward to advance the carrier to convey a button from the mouth of the chute along the guideway of the presser-foot into fastening position, wherein its shank is thrust against the stop-shoulder 17' of the presser-foot within the range of movement of the needle in one of its lateral positions. In advancing the bar 27, the two sections of the connecting rod remain initially locked together by means of the latch-lever 78 81, but are automatically unlocked before the end of its operative stroke by engagement of the latch-lever with the tripping stud 82. In the continued movement of the stop-lever 89, the thrust-collar 59 is arrested by engagement with the stationary seat 58, thereby positively arresting the movement of the rod section 69 and permitting the section 70 in its continued movement relative thereto to dis-tend the spring 72 which serves as a buffer to prevent excessive strain upon the button such as to break it or mar its appearance. In the retraction of the carrier by the automatic action of the stop-lever 89, the component sections 69 and 70 of the connecting rod are first drawn into initial relation and locked together by the spring 72 and latch-lever 78 81, after which the bar 27 is retracted and the button-carrier withdrawn into button-receiving position wherein the clamping jaw 35 is shifted outwardly by the action of the cam member 55 to admit the succeeding button. In its movements toward and from extreme positions, the button-carrier traverses an inclined path corresponding substantially with the inclination of the button-shank guiding slots of the chute and presser-foot relative to the top or work-supporting face of the throat-plate with which the fulcrum-pin 48 is disposed parallel and substantially beneath the pivotal connection of the swinging arm 46 with the carrier when the latter is in retracted or button-receiving position. The advance of the carrier toward fastening position is therefore in a downwardly inclined direction around the fulcrum-pin 48 as a center.

The present machine is preferably provided with a presser-foot lifter connected with and actuated by the stop-motion device, as represented for instance in the

United States patent of W. L. Barron, No. 998,595, of July 25, 1911. The presser-bar 10 has fixed thereon the collar 114 provided with the lug 115 adapted for engagement by the arm 116 of a tilting lever fulcrumed upon the stud-screw 117 and having a rearwardly extending arm 118 carrying a roller-stud 119 which is embraced by the forked forward extremity 120 of the forwardly extending arm 121 of the rock-lever mounted upon the fixed fulcrum-stud 122. This rock-lever has a rearwardly extending arm 123 laterally offset and provided with the socket 124 having the plunger-pin 125 whose reduced rearward end passes through said socket and is provided with the thrust-nut 126 and jam-nut 127 to sustain the thrust of the spring 128 encircling the same and interposed between the inner end of the socket and the enlarged forward end of the pin. When the stop-lever 89 is shifted into stopping position by the action of the spring 101, the plunger-pin 125 is thrust aside by the lateral movement of the collar 99, but in the depression of the plunger-bar 93 by the cam 94, as represented in Fig. 6, the plunger-pin 125 snaps over the upper end of the collar 99, and the subsequent rise of the plunger-bar 93 into the notch 96 in finally stopping the machine causes the rocking of the levers 121 123 and 116 118 to lift the presser-foot. In the setting of the stop-lever 89 for a new operation, the connections between the same and the button-carrier and presser-foot are so constructed and arranged that in the initial movement of the same the carrier-bar 27 is first advanced to bring its thrust-collar 59 against the stop-shoulder 58, thereby completing the first step of positioning a button *b* in the presser-foot within the range of action of the needle. The continued movement of the stop-lever under manual actuation completes the lateral movement of the collar 99 sufficiently to disconnect it from the plunger-pin 125, thereby permitting the presser-bar 10 to descend under the action of its spring 11 upon the collar 114 and seating the presser-foot firmly upon the material *m* interposed between the same and the work-support. During these two stages of operation, the upper end of the plunger has moved laterally through the notch 96 in the stopping cam and the belt has been shifted upon the tight pulley 112, but it is only after the release of the plunger-pin 125 from engagement with the collar 99 and the lowering of the presser-foot that the final disengagement of the plunger-bar 93 from the stopping cam 94 is actually completed to permit the starting of the shaft 95 for the button-fastening operation. By this means, as previously stated, the button is first conveyed along the raceway afforded by the lower end of the chute and the guideway of the presser-foot

into the range of action of the fastening means without imposition of any resistance produced by its forcible contact with the material resting upon the work-support; 5 the presser-foot is then lowered to firmly grip the work and seat the button securely thereon for the stitching operation; and the fastening operation cannot be begun until each of these preliminary actions have been 10 completed and the button and the work associated together in the required relation therefor.

The base 20 of the button-hopper has a depending bearing boss 20' in which is journaled the vertical shaft 129 having secured upon its upper end the agitator hub 130 provided with the radiating brushes 131 adapted to act upon the buttons substantially as described in the United States patent to J. J. 15 Sullivan No. 596,020, of December 21, 1897. The shaft 129 has fixed thereon by means of set-screws 132 a bushing formed with the hub 133 and the concentric bearing members 134 and 135, upon the latter of which 20 is secured the ratchet-wheel 136 having peripheral teeth adapted for engagement by the pawl 137. This pawl is fulcrumed at 138 upon the lateral ear 139 of a reciprocating bar 140 having a forked extremity embracing and supported by a transverse pin 141 of a bifurcated post 142 secured to and depending from the base 20. The other end of the bar 140 is pivotally connected by 25 means of the pin 143 to the forked extremity 144 of an upwardly extending arm 145 of a yoke-lever 146 mounted upon the fixed fulcrum-pin 147 and embracing the actuating cam 148 upon the main-shaft 95 from which it derives rocking movements and by means 30 of which the bar 140 is reciprocated. The pawl 137 is pressed normally in contact with the ratchet-wheel 136 by means of a spring 149 interposed between the bar 140 and a pin 150 upon the head of the pawl 137. 35 Fitted upon the bearing member 134 of the bushing is a strap 151 formed in one side with a recess 152 and provided with a radially extending tubular arm 153. Within the recess 152 is disposed the crescent-shaped brake-shoe 154 fitted to the periphery of the bushing member 134 and having in its opposite face a pocket 155 entered by the conical extremity of a plug 156 disposed within the arm 153 and forced against the 40 brake-shoe 154 by means of a spring 157 interposed between said plug and a screw-plug 158 in the internally threaded outer end of the arm 153 by means of which the pressure of the brake-shoe upon the member 134 may be regulated.

The base 20 of the hopper has a depending flange 159 carrying a pin 160 to which is connected one end of a spring 161 having its opposite end attached to the arm 153 and adapted to draw the latter in a direction

opposite that in which the shaft is normally turned by means of the pawl 137. The flange 159 has secured thereto by means of the screws 162 the foot 163 of a stop-arm 164 between which and the edge of the flange the arm 153 is adapted to move under the alternate action of the pawl 137 upon the ratchet-wheel 136 and the spring 161 acting directly upon the arm 153.

By the means just described, the arm 153, 75 normally resting against the stop-shoulder afforded by the edge of the flange 159, moves toward the stop-arm 164 in opposition to the spring 161 until it encounters the arm 164 when the strap 151 is permitted to slip upon the bushing member 134 a distance equivalent to the net advance movement of the agitator-shaft 129, and upon the retraction of the pawl 137 for a succeeding engagement with the ratchet-wheel 136 the retraction of the arm 153 by the spring 161 causes 80 a similar retrograde movement of the ratchet-wheel 136 until arrested by the encounter of the arm 153 with the shoulder of the flange 159 when the parts are arrested 85 for an advance movement under the succeeding action of the pawl 137. By means of this mechanism, while the agitator receives a progressive step-by-step movement under the action of the ratchet-and-pawl device, 90 each movement is succeeded by a retrograde movement in the opposite direction which insures a thorough agitation of the buttons and a dislodgment of any which meet with 95 obstruction produced by the jamming of several together or the encounter of one of the brush lifters or button diverting members of the hopper.

Having thus set forth the nature of the invention, what we claim herein is:— 105

1. The combination with stitch-forming mechanism, and a work-support, of a presser-foot provided with a button-raceway and movable toward and from said work-support, a button-carrier adapted to convey a button along said raceway for a stitching operation, and successively acting means for operating the carrier to introduce a button in said raceway and lower the presser-foot. 110

2. The combination with a shaft, stitch-forming mechanism operatively connected with said shaft, a stop-motion for controlling the action of said shaft, and a work-support, of a presser-foot provided with a button-raceway and movable toward and from said work-support, a button-carrier adapted to convey a button along said raceway for a stitching operation, means connected with the stop-motion for operating the carrier to introduce a button in said 120 raceway, and means independent thereof and controlled in its action by said stop-motion for lowering the presser-foot thereafter.

3. The combination with a shaft, stitch- 125

forming mechanism operatively connected with said shaft, a stop-motion for controlling the action of said shaft, and a work-support, of a presser-foot provided with a 5 button-raceway and movable toward and from said work-support, a button-carrier adapted to convey a button along said raceway for a stitching operation, means connected with the stop-motion for operating the carrier to introduce a button in said raceway, and means independent thereof and controlled in its action by said stop-motion for lowering the presser-foot thereafter, the carrier operating and presser-foot controlling 10 connections with the stop-motion being arranged to perform their functions successively in the order named and prior to the completion of the action of the stop-motion in inaugurating the operation of 15 said shaft to produce a stitching action.

4. The combination with button-fastening means and a button-raceway, of a carrier adapted to convey a button into fastening position, manually controlled means for 20 moving said carrier in one direction, means for moving said carrier in the opposite direction and an automatically acting controlling device for said means.

5. The combination with button-fastening 30 means and a button-raceway, of a carrier adapted to convey a button into fastening position, manually operated means for advancing the carrier to place a button in fastening position, means for retracting said 35 carrier to receive the succeeding button and an automatically acting controlling device for said means.

6. The combination with a work-support, button-fastening means and a button-race- 40 way, of a reciprocating carrier adapted to convey a button into fastening position, a plurality of swinging supporting arms spaced apart and pivotally connected with said carrier, and means for reciprocating 45 the carrier.

7. The combination with a work-support, button-fastening means and a button-race- 50 way leading into fastening position, of a reciprocating carrier adapted to convey a but- ton along said raceway into fastening position, a plurality of swinging supporting arms mounted upon parallel fulcrsa and spaced apart and pivotally connected with 55 said carrier, and means for reciprocating the carrier.

8. The combination with a work-support, button-fastening means, and a button-race- 60 way downwardly inclined toward the work-support and leading into fastening position above the same, of a reciprocating carrier adapted to convey a button along said raceway into fastening position, a swinging supporting arm mounted upon a fulcrum sub- 65 stantially parallel with and below the oper- ative face of the work-support, and pivot-

ally connected with the button-carrier ad- jacent its button-holding portions, and means for reciprocating the carrier.

9. The combination with a work-support, button-fastening means and a button-race- 70 way leading into fastening position, of a reciprocating carrier adapted to convey a button along said raceway into fastening position, a plurality of swinging supporting arms mounted upon parallel fulcrsa disposed at the opposite side of the operative face of 75 said work-support from the carrier and spaced apart and pivotally connected with said carrier, and means for reciprocating the carrier.

10. The combination with button-fastening means and a button-raceway, of a reciprocating carrier provided with a spring-pressed button-engaging jaw and adapted to convey a button into fastening position, sup- 85 porting means for said carrier including a swinging arm pivotally connected therewith, means carried by said swinging arm for controlling the movement of said jaw into and out of forcible engagement with a button 90 sustained within the range of action of the carrier, and means for reciprocating the carrier.

11. The combination with button-fastening means and a button-raceway leading 95 into fastening position, of a reciprocating carrier provided with a spring-pressed but- ton-clamping jaw and a rigid button-pro- pelling jaw and adapted to convey a button along said raceway into fastening position, 100 supporting means for said carrier including a swinging arm pivotally connected therewith, means carried by said swinging arm for moving the button-clamping jaw later- 105 ally toward and from said raceway, and means for reciprocating the carrier.

12. The combination with button-fastening means and a button-raceway leading into fastening position, of a reciprocating carrier comprising an endwise reciprocating 110 bar and a spring-pressed rock-lever pivot- ally mounted thereon and provided with a button-engaging jaw, supporting means for said bar including a swinging arm, means for imparting endwise movements to said 115 bar, and a cam-member carried by said swinging arm and adapted to engage said rock-lever for imparting lateral movement to its button-engaging jaw.

13. The combination with a work-sup- 120 port, button-fastening means and a button- raceway, of a reciprocating carrier movable in a path inclined to and beneath a portion of said raceway and provided with a button- engaging jaw, a spring detent-finger carried 125 by and extending in advance of said jaw, and means for actuating said carrier.

14. The combination with a work-sup- 130 port, button-fastening means and a button- raceway leading into button-fastening posi-

tion, of a reciprocating carrier movable in a path inclined to and beneath a portion of said raceway and provided with a laterally movable spring-pressed button-engaging jaw 5 having a spring detent-finger sustained in advance thereof, and means for actuating said carrier.

15. The combination with the frame comprising a standard with laterally extending 10 work-supporting arm and an overhanging bracket-arm, and button-fastening means, of a button-chute sustained by the bracket-arm, a presser-foot formed with a button-guideway and also sustained by the bracket-arm with its guideway in register with the mouth of said chute, a carrier for conveying buttons from the chute to fastening position within the presser-foot and comprising an endwise movable bar substantially parallel 20 with and disposed intermediate the arms of said frame, and means for imparting endwise movements to said bar.

16. The combination with button-fastening means and a button-raceway leading 25 into fastening position, of a reciprocating carrier adapted to convey a button along said raceway into fastening position, and actuating means therefor including a rod 30 constructed in two relatively movable sections yieldingly connected together and provided with locking means for maintaining them in fixed relation, and means for unlocking said sections during the operative movement of said rod.

35. 17. The combination with button-fastening means and a button-raceway leading into fastening position, of a reciprocating

carrier adapted to convey a button along said raceway into fastening position, and actuating means therefor including a rod 40 constructed in two relatively movable sections, one of which is formed with a shoulder and the other of which carries a spring-pressed latch-lever adapted for engagement with said shoulder, a spring for normally 45 maintaining said sections in initial relation, means for reciprocating said rod, and a stationary tripping element within the path of movement of said latch-lever and adapted to disengage the same from said shoulder in 50 the movement of said rod between extreme positions.

18. The combination with button-fastening means, a button-chute leading thereto, and a button-hopper for supplying buttons 55 to the chute, of an agitator within said button-hopper, a rotary agitator shaft, ratchet-and-pawl mechanism for imparting to said shaft step-by-step rotary movements in one direction, an element frictionally mounted 60 upon said shaft, a spring acting thereon in opposition to the action of the ratchet-and-pawl mechanism, and a stop member for limiting the movement of said element under the action of said ratchet-and-pawl 65 mechanism.

In testimony whereof, we have signed our names to this specification, in the presence of two subscribing witnesses.

JOHN J. SULLIVAN.
ALBERT F. FIFIELD.
